(57) **CLAIM**

The ornamental design for an egg carton, as shown and described.

DESCRIPTION

FIG. 1 is a top plan view of an egg carton according to our new design;

FIG. 2 is a front elevational view thereof;

FIG. 3 is a right-side elevational view thereof, the left-side view being a mirror image of FIG. 3;

FIG. 4 is a rear elevational view thereof;

FIG. 5 is a bottom plan view thereof;

FIG. 6 is a perspective view thereof;

FIG. 7 is a perspective view thereof in a partially opened condition; and,

FIG. 8 is a plan view of the interior of the egg carton in a fully opened condition.
